ADJUSTABLE GARMENT HANGER SUPPORT

Filed Sept. 23, 1949

UNITED STATES PATENT OFFICE

2,634,892

ADJUSTABLE GARMENT HANGER SUPPORT

Theodore J. Wachowski, Wheaton, Ill.

Application September 23, 1949, Serial No. 117,446

4 Claims. (Cl. 224—29)

1

My novel invention relates to a new and useful clothes rack which is adapted to be used in automobiles. It is the purpose of my invention to provide an automobile clothes rack which is vertically adjustable so that the maximum vertical length of any automobile, in which my device is used, may be utilized in hanging garments. It is additionally an object of my device to provide a garment hanging rack which is adjustable in the direction of the longitudinal axis of the automobile so that the maximum longitudinal dimension afforded for the positioning of my novel device may be utilized for hanging garments or the like. Additionally, it is my object and purpose to provide an easily portable device which may be removed from the automobile when desired, and one which is easily assemblable and easily adjustable because of the provision of the multiplicity of cooperating telescoping elements for adjusting my clothes rack as desired.

All the prior devices in this art have proven unsatisfactory because the maximum dimensions of the car were not utilized in hanging garments. The majority of devices in the same art as mine have been adapted solely for use in hanging garments across the transverse dimension of the automobile. It will be understood that devices of this nature are undoubtedly unsatisfactory for a number of reasons. Among the reasons for the aforesaid unsatisfactoriness is the obscurance of rear view vision caused by the garments being hung across the transverse dimension of the automobile. If it is desired to unobscure the transverse dimension with the aforesaid prior devices, it is necessary either to substantially lower the height of the horizontal member which is utilized in said prior devices or limit the hanging of clothing to the lateral portions of the supporting element. It will be immediately apparent that either valuable height will thus be lost or that the number of garments which can be hung is exceedingly limited. Another objectionable feature of the garment supports which extend transversely is that access to the interior of the car is usually impaired or made difficult because there is a substantial blocking of the doorways in the rear portion of the car by the hanging garments, and in the case of the two-door model cars, it will be readily appreciated that great effort would be required to gain access to the rear portion of the car in which the garments would be hanging. Another objectionable feature of the transverse type of clothes hanging racks results from the fact that the front portion of the rear seat is exceedingly near the rear portion of the back of

2

the front seat. Of course garments hung along the priorly known devices of the "transverse" type could only hang freely the full length between the front of the rear seat and the back of the support of the front seat.

Now my device completely eliminates all the aforesaid objections and difficulties and allows free access to the rear portion of the car even when the garments are hanging, and furthermore it does not obscure the rear view vision and is adapted to permit the hanging of numerous garments the full vertical dimension of the interior of the car. My novel device is adapted to be mounted in the automobile, in which the same is to be used, along one side of the car.

To my knowledge, there have been only two prior devices in this art which permit the hanging of garments on a rack which extends longitudinally with respect to the dimension of the automobile. The one device is objectionable because it requires that it be bolted to the automobile. Of course many individuals, who have need for clothes hanging racks, would be exceedingly reluctant to bolt a rack to the interior of an automobile for obvious reasons. The other of the devices, although it permits hanging garments on a bar extending longitudinally with respect to the car, it is objectionable because it does not and cannot utilize the space provided between the front and rear seats.

Because garments hung on my device are hung on an adjustable horizontal bar which extends parallel to the longitudinal axis of the automobile, it will be understood that a number of garments, as long as the distance from floor to ceiling may be hung without crushing or folding.

Other and further objects of my invention will become apparent from the following description and appended claims, reference being made to the accompanying drawings and numerals of reference thereon.

On the drawings:

Fig. 1 is an elevational view of my device showing same mounted in position in an automobile, portions of the automobile being broken away, and showing, in dotted lines, a modified positioning to utilize the maximum height from ceiling to floor.

Fig. 2 is a plan view of my device looking at the righthand side of the device in Fig. 1.

Fig. 3 is one form of extensible joint mechanism which may be used.

Fig. 4 is another modified and optional form of the extensible joint which may be used.

Fig. 5 is a perspective view of a swivel joint.

which connects the horizontal supporting bar with its respective standard.

Referring to the drawings, numeral 10 designates the floor of an automobile. Numeral 11 represents the front seat of an automobile and numeral 12 designates the rear seat. In the usual sedan which is indicated by numeral 14 there is a recess or well 15 between the rear portion of the automobile and the back of the rear seat 12.

It will be observed that my novel device has a pair of standards including a front or forward standard and a rear or back standard. The front standard comprises a pair of elongated preferably hollow pivotable legs indicated by the numerals 16 and 17, said legs being angularly disposed with respect to each other. For the purpose of adding rigidity, I provide a cross bar or supporting member 18.

In order to permit adjustment of the height of the front standard extensible legs or rods 19 and 20 are telescopically mounted with respect to standard legs 16 and 17. Preferably, each of the rods 19 and 20 has a rubber cap or friction member 21 at its outer end.

It will be observed that by providing independently adjustable legs 19 and 20 and preferably legs 25 and 26 (which will be hereinafter described), stability of my novel device may be achieved regardless of a variation or irregularity in the contour of the supporting surface.

The normally rear standard comprises a pair of pivotable legs 22 and 23 as illustrated in Fig. 2 and which are angularly disposed with respect to each other. Numeral 24 represents a cross bar connecting legs 22 and 23 and is provided for the purpose of adding rigidity. In a preferable form of my invention, I provide legs or rods 25 and 26 which are slidably and extensibly mounted within rear standard legs 22 and 23 respectively. At their outer ends, the adjustable legs 25 and 26 have securely mounted thereon friction members such as rubber caps 27.

At the normally uppermost portion of each of the standards which I shall designate as A and B the legs are flattened and compressed as is clearly illustrated in Fig. 5 by the numeral 28. To connect the legs of the respective standards A and B at their uppermost ends, I provide a passaged cylinder 29, the end surfaces of which bear against respective flattened portions 28 of the legs of the respective standards. A bolt or screw 30 having an adjustable wing nut 31 mounted on one end thereof passes the respective legs and the cylinders 29. From the foregoing, it will be understood that the cylinder 29 is a swivel joint and that the respective standard A or B may be pivoted as desired and locked into position with respect to the respective cylinder 29 by tightening the wing nut 31. Each of the cylinders 29 carries a stud or arm 32.

Numeral 33 designates an elongated tube which at one end thereof is mounted on a stud or arm 32 of the cylinder 29 of standard A. Tube 33 is adapted to be positioned parallel to the longitudinal axis of the automobile and to one side of the longitudinal mid-line. Preferably the normally forward end of the tube 33 is mounted on arm or lug 32 and is retained thereon by frictional engagement. Numeral 34 designates a tube which has a smaller outer diameter than the inner diameter of tube 33, and it will be seen that same is adapted to telescopically slide within the normally rearward end of the

tube 33. Tube 34 frictionally engages the arm or stud 32 of the rear standard B. It will be appreciated that to obtain the proper frictional engagement of tube 34 on stud 32 of the rear standard B that said stud of the rear standard B should be of smaller diameter than the stud 32 of the forward standard A.

The arrangement of parts heretofore described may be optionally changed without departing from the concepts herein embraced, and so that the extensible tube 34, instead of being mounted on the stud 32 of standard B, is mounted on the stud or standard A and the tube 33, instead of being mounted on the stud 32 of standard A, is mounted on the stud 32 of standard B.

Referring to Fig. 1, it will be noted that I illustrate two of the positions which my novel device may assume. The position indicated in the dotted line utilizes the entire vertical height from the floor 10 of the vehicle to the roof thereof. In order to retain hanging garments from slipping on the rack, I employ separators, dividers or abutment members 35 which are mounted on the longitudinal rod or tube of my novel rack, but which may be adapted to be moved as desired to various positions. These abutment members 35 are adapted to engage portions of a hanger which are hung around the bar 33.

In order to provide an easily operable means for adjusting the various extensibly adjustable lengths I preferably employ the combination of elements which is illustrated in Fig. 3. The following description although relating to the tubes 33 and 34, describes a mechanism which I preferably employ to extensibly connect the extensible legs of standards A and B respectively. It will be noted that an apertured collar 36 is removably mounted on the normally rearward end of the tube 33, and it will also be noted that the end of the tube 33 is apertured as illustrated at 37. I employ an element such as a set screw 38 to secure collar 36 to the end of the tube 33. It will be seen that collar 36 has an end annular flange 39. The end of the tube 34 is extensibly mounted within the end of the tube 33 and a split sleeve 40, having an annular end flange 41 which is normally in abutment with the flange 39, is mounted around the tube 34 within the tube 33. When it is desired to adjust the length of the bar, comprising the tubes 34 and 33, a wing screw 42 which extends through the collar 36 is released from engagement with the sleeve 40 so that the same is permitted to expand from frictional engagement of tube 34 and said tube, may either be extended or moved inwardly to the desired position and retained thereat by tightening the screw 42 to cause the sleeve 40 to frictionally engage the tube 34 and hold same in adjusted positions.

A more economical adjusting means for adjustment of the extensibly adjustable elements of my novel device may be optionally employed. Such optionally adjustable mechanism is illustrated in Fig. 4, and it will be noted that the normally forward end of the tube 34 is provided with a plurality of pairs of aligned apertures 43. The end of tube 33 is provided with preferably one pair of aligned apertures through which a bolt 44 extends. A wing nut 45 is adapted to retain bolt 44 in the aligned apertures of the tube 33. When it is desired to adjust the effective length of the clothes supporting element, any pair of aligned apertures 43 are aligned with the apertures in tube 33, as desired, and the bolt 44 is mounted in position as described above.

The foregoing description of the optional means relates to the optional adjustment of the extensible mechanism of the clothes supporting element, however, the same mechanism may be optionally employed for extensibly connecting the extensible end legs of standards A and B.

As many changes could be made in the above construction, and as many apparently widely different embodiments of my invention within the scope of the claims could be constructed without departing from the spirit and scope thereof, it is intended that all matter contained in the accompanying specification shall be interpreted as illustrative and not in a limiting sense.

I claim:

1. An adjustable garment hanger support device for use in an automobile body comprising a front standard having a pair of adjustable extensible legs disposed in angular relation, the lower ends of said legs being adapted to rest on the floor of the body rearwardly of the front seat of the body; a rear standard having a pair of adjustable extensible legs disposed in angular relation, the lower ends of said legs being positionable rearwardly of the rear seat of the body; an adjustably extensible rod structure extending between the upper ends of said standards, said structure including a pair of tubes arranged in interfitting telescopic relation; means pivotally connecting each end of said rod structure to the upper end of a respective standard whereby each standard is capable of pivoting relatively about an axis normal to the longitudinal axis of said rod structure, said means including a pair of bearing cylinders, the end faces of each of said bearing cylinders being received between the upper ends of the legs of a respective standard, each of said bearing cylinders having a stud projecting normally therefrom releasably insertable in one end of a respective tube; and means for clamping the upper ends of the legs of each standard to a respective bearing cylinder to thereby lock each standard in various positions of angular adjustment with respect to the longitudinal axis of said rod structure.

2. An adjustable garment hanger support device for use in an automobile body comprising a pair of standards; an adjustably extensible rod structure extending between the upper ends of said standards, said rod structure including a pair of tubes arranged in interfitting telescopic

relations; means pivotally connecting each end of said rod structure to the upper end of a respective standard whereby each standard is capable of pivoting relatively about an axis normal to the longitudinal axis of said rod structure, said means including a pair of bearing cylinders, each of said bearing cylinders having a stud projecting normally therefrom releasably insertable in one end of a respective tube; and means for clamping the upper end of each standard to a respective bearing cylinder to thereby lock each standard in various positions of angular adjustment with respect to the longitudinal axis of said rod structure.

15 3. The combination as set forth in claim 2, in which each of said standards is provided with a pair of adjustably extensible legs disposed in angular relation.

4. An adjustable garment hanger support device for use in an automobile body comprising a pair of spaced-apart standards, each of said standards being provided with a pair of adjustable extensible legs; a rod structure extending between the upper ends of said standards, said 20 rod structure including a pair of tubes arranged in interfitting telescopic relation whereby they are positionable with respect to each other to vary the distance between said standards; means for releasably securing said tubes in the various 25 adjusted positions; means pivotally connecting each end of said rod structure to the upper end of a respective standard, said means including a pair of studs, each of said studs being releasably insertable in one end of a respective tube; and means for locking each standard in various 30 positions of angular adjustment with respect to the longitudinal axis of said rod structure.

35 THEODORE J. WACHOWSKI.
